UNITED STATES PATENT OFFICE.

GUY H. HUBBARD, OF SHELBURNE FALLS, MASSACHUSETTS; CLARISSA A. HUBBARD
ADMINISTRATRIX OF SAID GUY H. HUBBARD, DECEASED.

MACHINE FOR PARING AND SLICING APPLES.

Specification of Letters Patent No. 16,517, dated January 27, 1857.

To all whom it may concern:

Be it known that GUY H. HUBBARD, deceased, late of Shelburne Falls, in the county of Franklin and State of Massachusetts, did 5 invent certain new and useful Improvements in Apple-Slicers, and it is hereby declared that the following, in connection with the accompanying drawings, which constitute a part of this specification, is a 10 full and exact description thereof, as attached to a paring-machine constructed under Letters Patent issued to S. N. Maxam, April 10, 1855.

The machine is secured to the table by 15 means of the clamp, A, and to this is attached the standard, B, by means of the strong joint at B', which permits the careening of the machine both right and left.

E, is the driving wheel, motion being 20 given by means of the crank to all the parts. Upon the face of the driving wheel, E, is an inclined scroll, F, upon which one end of the rack bar, G, slides; this rack bar connects with, and gives motion to, the loop 25 gear, H, which supports and guides the spring rod, I, upon which is affixed the paring knife, J.

The machine being careened to the right as shown in red outline in Fig. 1, as the 30 operator stands in position to seize the crank with his right hand, an apple is placed upon the fork, K, when, by rotation of the crank, the driving wheel, E, gives motion to the pinion E' and thence to the fork and apple, 35 while the scroll, F, acting through the rack bar, G, upon the loop gear, H, the paring knife, J, is thereby passed, during the rotation of the apple, from its base around to its outer end, and effectually pares the 40 apple, when the outer circuit of the scroll, F, having passed the end of the rack bar, G,—the coiled spring, S, attached to the outer end of the rack bar, contracts, and returns the rack bar, loop gear, spring rod 45 and paring knife, to their original positions in readiness to repeat the operation of paring. The apple thus pared is in readiness for the action of the slicer, which is constructed and arranged as follows:—To the 50 standard, B, is hinged at N', a strong arm of iron, N, sustaining the cross gage head,

P, to which is affixed the curved knife, O, in such position that the edge thereof alines near the axis of the fork, K, and swinging upon the hinge at N', in a plane nearly 55 parallel to said axis. A tripping post, M, is attached to the clamp, A, which, on careening the machine to the left, comes in contact with the pin, L, passing through the shaft of the loop gear, H, and causes 60 the partial rotation of the loop gear, H, and thereby withdraws the end of the rack bar, G, from the scroll, F, thus permitting the backward rotation of the crank and driving wheel, together with the fork and apple. 65 The machine being now careened to the left, as described, and the pared apple remaining upon the fork, the arm, N, with the slicing knife, O attached, is swung by the left hand and the knife pressed lightly against the 70 apple, which is thereby cut, during its backward rotation, into one continuous slice or ribbon, leaving only the core in cylindrical form upon the fork. The careening of the 75 machine perfectly accomplishes the separation of the slices from the parings by depositing each in somewhat widely separated positions or receptacles, while the parabolic curvature of the knife produces such a formation of slices that they do not pack closely 80 together while drying, and yet are not in the least objectionable for immediate cooking.

The arm, N, may be so hinged to the 85 standard as to swing perpendicular to the axis of the fork, if desired to commence the slicing at the equator of the apple, yet the present arrangement is deemed preferable. The detaching of the rack bar from the scroll, and an equivalent detaching of the 90 feed gear, in other machines to which the slicer may be attached, I have accomplished without the tripping-post, M, by the use of the lug or cam upon the hinge-frame of the arm, N, as shown at R, Fig. 2, but prefer 95 the tripping post as described.

I do not claim the cutting of apples into continuous slices, or ribbons; nor any formation of slices to prevent their close packing while drying. Neither do I claim, nor 100 confine myself to, any particular curvature of the knife, O, nor the application of the

arm, N, and knife, O, to the particular machine represented, several different ones being equally appropriate therefor, but

What I do claim as my invention and desire to secure by Letters Patent, is—

The arrangement of the machine with its paring and slicing knives in such a manner as to careen upon the joint B' in the man-

ner and for the purpose substantially as set forth.

CLARISSA A. HUBBARD,
Executrix of the will of the said Guy H.
Hubbard.
